UNITED STATES PATENT OFFICE.

ISAAC F. RUBEL, OF CHICAGO, ILLINOIS.

DESIGN FOR A KNIFE-HANDLE.

SPECIFICATION forming part of Design No. 16,687, dated May 11, 1886.
Application filed March 22, 1886. Serial No. 196,130. Term of patent 3½ years.

To all whom it may concern:

Be it known that I, ISAAC F. RUBEL, a citizen of the United States, residing at Chicago, in the county of Cook and State of Illinois, have invented a certain new and original Design for Knife-Handles, of which the following is a specification, reference being had to the accompanying drawing, forming part thereof.

Said drawing is a view of one side of a knife whose handle contains my design.

A is the bolster. A' is the tip. B is the scale or side piece of the handle. B' B' are the figures, which are the distinctive and essential characteristics of my design, on the bolster and tip, respectively. Said figures consist each of an annulus, b', having a large sectoral projection, b", extended toward the

middle of the handle, and two smaller projections, b" b", opposite the larger.

I claim—

The design for a knife-handle herein shown and described, wherein are the figures on the bolster and tip, consisting of an annulus with a large sectoral projection and two smaller projections opposite the larger.

In testimony whereof I have hereunto set my hand, in the presence of two witnesses, at Chicago, Illinois, this 9th day of March, A. D. 1886.

ISAAC F. RUBEL.
